MOTORLESS BOAT PROPELLER

Efstratios H. Phillas, New York, N. Y.

Application October 26, 1942, Serial No. 463,375

4 Claims. (Cl. 74—42)

This invention relates to so-called motorless boats, meaning particularly small craft which may be driven by oars operated by the occupant, or by small units of gasoline motor mechanism such as can be lifted by hand termed out-board motors and which may be installed in or removed from the vessel by the operator.

The object of this invention is the construction and arrangement of a special system of levers or bars and the connections thereof pivotally and movably whereby it is intended to assist at the start and during the operation the rotation of the propeller mechanism in the direction desired, forward or backward at will, and to enable the movement of the combined parts to be stopped or accelerated in an emergency such as a necessity for arresting or reversing the progress of the boat suddenly. The individual expressions employed to identify the different elements in the following description are chosen only for the purpose of explanation. Furthermore, this applicant has in contemplation the introduction in the same boat of two sets of the given devices herein described and specified, and the attachment of two propellers spaced apart at the stern and adapted to be rotated in the same or in opposite directions for turning or steering the moving vessel.

Accompanying this application and forming a part of the specification are drawings of the invention, and Fig. 1 represents a side view showing all parts assembled with the auxiliary recessed lever and the extended end of the main driving bar attached.

Fig. 2 is a side view of all the co-acting parts showing the main driving bar and auxiliary lever detached, and the pressure lever in lowered contacting position.

Fig. 3 is an enlarged view of the upper portion of the hand lever, showing the devices carried by the hand lever and the side spring positioning the auxiliary lever bar.

Throughout the drawings and description the same number is used to refer to the same part.

Considering the drawings, 1 refers to the bottom of the boat to be propelled, of which 2 is the propeller blade and 3 the propeller shaft. It is to be understood that the construction illustrated may be modified in practice to locate the operating levers system so that the operator will face towards the bow of the boat instead of the stern as shown. The mitre gearing 4 is directly driven by the intermediate toothed and mitre gear wheel 5 meshing with the main driving gear wheel 6. 55

A hand lever 7 having one end pivoted to the base plate of the apparatus is connected by the main driving lever bar 8 with the main driving gear wheel 6 and the hand lever 7. It will be observed that one end of the lever 8 has a partly circular termination 9, and an auxiliary bar 10 has in its edge the recesses 11 and 12 corresponding in form to the termination 9. The recesses and the termination are constructed to be engaged and disengaged, and there will be noted directly below the termination 9 a socket recess 13 arranged to receive the end of the spring catch 14 on the end of the pivoted piece 15 provided with the pivot pin 16. A pin 17 at the end of the piece 15 is connected by means of the coil spring 18 with the pin 19 shown between the recesses 11 and 12 on the auxiliary lever bar 20. When the spring catch 14 is engaged with the socket 13 the recess of the auxiliary lever and the termination 9 of the main driving lever bar 8 are connected and yieldingly so held. It will be noted in both Figs. 1 and 2 that the end of the main driving bar which has rounded termination 9 extends for a distance beyond the pivotal connection of the driving bar and the hand lever. Reference number 21 indicates the pivotal fulcrum of the lengthwise lever 20 on the hand lever 7. As best shown in Fig. 3, the side springs 22 and 23 which are carried by the upper portion of the hand lever are caused to press equally against the sides of the upper end of the lever 20, and serve to position that lever yielding and aligned as indicated with the hand lever. If found necessary due to the requirements of any particular service of the boat equipped with this invention, a coil spring 24 may be attached to the end of lever 20 as shown and to the pin 25 on lever 7 to assist in holding the lever 20 lengthwise in position in line with the hand lever.

40 The lever system also comprises three co-acting lever bars of which the lower lever 26 has one end attached to the pivotal connection 21 on the main driving gear 6, which is also the connection for the main driving lever bar 8. The middle lever 28 has a slot 30 substantially half way between its ends and the lower lever has an end pin 29 engaging that slot. The middle lever has a pivotal connection 31 with the upper or pressure lever 32, and the other end of the middle lever 28 has a pivotal connection with the hand lever in common with the main driving bar 8. The pressure or upper lever 32 has an angular or convergent end 33 formed to contact with the stop lug 34 on lower lever 26 when the

pressure lever is in its engaging position as illustrated in Fig. 2.

As best shown in Fig. 3 the upper or pressure lever 32 has a slot lengthwise marked 35 and a pin 26 on the upper end of the lengthwise lever 20 engages the slot 35. To limit the length of the slot 35 in the pressure lever 32 there are provided two spaced sliding pin or similar devices such as the pin 37, the pins 37 or plugs being held in their uppermost positions and out of the slot 35 in the pressure lever 32 by the springs such as the spring 38. The springs engage the top ends of the pins by a suitable connection and the pins are held up until forced downwardly across the slot 35 by the contact of the lugs such as the lug 39 on the sliding hand operated bar 40, as best shown in Fig. 3.

To follow the operation of this invention the drawings will be considered with the following explanation. Assume the parts to be in the positions drawn in Fig. 1, with the main driving bar or lever upon or near a dead center with the main gear wheel. The recessed lever bar and the rounded termination of the extended end of the driving bar are connected and so held by the engagement of the socket and spring latch described. Now, the movement by the occupant of the boat of the upper end of the hand lever to the left will exert a yielding pull by the recessed lever on the extended end of the main driving bar and will assist the clockwise rotation of the main gear in starting or in regular rotation. Then assume that the top end of the main hand lever has reached the limit of its movement to the left and the main driving bar extends across the main gear wheel in the dead center line. A pull by the top of the hand lever to the right, causes the recessed lever to press the extended end of the main driving bar down and thus assist the start or continued rotation clockwise.

Again, assume that a reverse movement is desired. The main driving bar and recessed lever are separated, and the slot in the upper pressure lever limited by the pins specified. The angle end of the pressure lever is moved down into contact with the lug on the lower lever, and rotation of main driving gear wheel counter-clockwise is assisted. As the main gear and main bar connections approach the other side position on dead center by movement of the top end of the hand lever to right, the action of the slot and pin coupling of the lower lever and the middle or intermediate lever exerts a yielding pull up on the system also counter-clockwise and reversed as desired. The limiting of the slot in the pressure lever as herein explained, enables the operator to work the parts faster and if required to apply added force to the operation.

Having now described this invention, I claim:

1. In apparatus of the character described having in combination with a support, a main driving gear wheel, a system of levers comprising a hand lever having one end pivotally upon said support, a main driving bar pivotally connected with said main driving gear and with said hand lever, the end of said bar extending to one side of the hand lever and having a half circular termination, an auxiliary bar having one edge recessed to engage detachably said termination of the driving bar, a spring connecting said driving bar termination and the auxiliary bar, releasable

devices constructed to hold said spring under tension, a lever pivotally carried lengthwise by the hand lever and pivotally connected with said auxiliary recessed bar, side springs constructed and arranged to hold the said lengthwise lever in resiliently yielding position, and a plurality of co-acting additional levers pivotally and movably connected whereby one of said additional levers may be caused to exert pressure on said driving bar, said lengthwise lever having a projecting pin, and said pressure lever having a slot engaging said pin whereby said co-acting levers are actuated.

2. In apparatus of the character described, the combination of a main driving gear wheel, a pivoted hand lever, a main driving bar pivotally connecting said hand lever and main driving gear, a system of three additional levers, one of said levers being connected with said main driving gear wheel at one end, a pressure lever having a lengthwise slot, said hand lever provided with a pin engaging said slot, a connecting lever pivotally attached at its ends to said main driving bar and said pressure lever, and said pressure lever and connecting lever being constructed with slot and slot engaging pin devices pivotally joining said pressure and connecting levers, as shown and described.

3. An apparatus of the character described, comprising in combination a hand lever, a main driving gear, a main driving bar pivotally connected with the hand lever and main driving gear, said bar extending at one end beyond the pivot of the bar and hand lever, an auxiliary bar, the extended end of the said main driving bar and said auxiliary bar lever having mutually engaging releasable devices whereby the extended end of the said driving bar and said auxiliary bar can be connected and disconnected, a lever carried lengthwise by the hand lever and having one end pivotally connected with an end of said auxiliary bar at a distance above the pivotal connection of said main driving bar and hand lever, and side springs carried by the hand lever whereby said lengthwise lever is yieldingly and resiliently held in position aligned with the hand lever.

4. An apparatus of the character described, comprising in combination a pivoted hand lever, a main driving gear wheel, a main driving bar pivotally connected with the said hand lever and main driving gear wheel, a system of levers consisting of three levers including a lower connecting lever having one end pivotally connected with the connection of said main gear wheel and said main driving bar, an intermediate connecting lever, and an upper pressure lever, said intermediate lever having its ends pivotally connected with said main driving bar and said pressure lever, said lower lever and said intermediate connecting lever provided with movably and pivotally engaging slot and pin devices whereby the movement of the hand lever draws the end of the pressure lever down upon said lower lever, said lower lever having a stop lug engaging the end of said pressure lever, said hand lever carrying a projecting pin, and said pressure lever being constructed with a longitudinal slot engaging said pin whereby a movement of the hand lever will exert pressure by the end of the pressure lever upon the said lower lever.

EFRSTRATIOS H. PHILLAS.
